TELEVISION SYSTEM

Manfred von Ardenne, Berlin-Lichterfelde, Germany, assignor to Fernseh Aktiengesellschaft, Berlin-Zehlendorf, Germany

Application April 18, 1939, Serial No. 268,460
In Germany March 29, 1938

2 Claims. (Cl. 178—5.4)

This invention relates to television systems and more particularly to television reproduction in natural colours and to stereoscopic television.

An object of the invention is to provide a novel apparatus for improving the quality of electro-optically produced images.

Another object of the invention is to provide improved means for producing in a receiver pictures with exactly coinciding differently coloured components and to produce multicoloured pictures free from flicker.

Another object of the invention is to provide a television receiver for reproducing multicoloured and stereoscopic images, which is simple in construction and includes preferably a cathode ray tube as a source of light. This cathode ray tube has preferably a screen, containing only a small number of light emitting areas, each area emitting light of a different wave length. Instead of the screen composed of areas of different light emitting properties, it is also possible to use a small number of stationary colour or polarising filters.

It is a further object of the invention to overcome the difficulties existing in all hitherto suggested methods for receiving multicoloured images.

According to the invention three differently coloured or two stereoscopic lines of a picture are produced in a receiver adjacent to each other. A picture of these lines is viewed or projected by means of an electrical or optical compensating device in such a manner, that the lines appear coincident for the observer. The compensating device is moved in synchronism with the scanning of the lines, so that the scanning component having a direction vertical to the direction of the lines is compensated. The lines do not only coincide geometrically on the viewing screen, but also with regard to time, so that there appears no flicker.

My experiments concerning the effect of the absolute number of picture elements per image on the definition show that with small numbers of picture elements the sharper and better defined black and white image is always preferred to the less defined coloured image or stereoscopic image. The experiments show however, that there exists a critical number of picture elements, beyond which a further increase in the number of picture elements results in only a slight improvement of the image and that this improvement is not as great as that when use is made of coloured or stereoscopic images. This number of picture elements is in the order of

100,000 with the standard black and white image. The television standard used to-day with 441 lines and 230,000 picture elements is high above this critical value, so that with the frequency bands in use at the present time it would be an improvement to change over to coloured or stereoscopic television images. This shows the great practical importance of workable technical solutions of this problem particularly on the receiving side.

For the reception of television images the cathode ray tube is being made use of in most cases. The cathode ray tube however makes special difficulties in this respect. It has been suggested to use a screen divided in adjacent differently coloured lines over its entire surface. This method has however the drawback, that the luminescent screen must be composed of lines of luminescent material corresponding with a precision of 1% with the lines drawn by the cathode ray. This precision cannot be obtained with the means to-day available for deflecting the cathode ray. In consequence of the limited precision of the deflection all methods must be excluded, in which the lines of the cathode ray must be brought to coincidence with lines mechanically produced on the screen. The same holds true with regard to stereoscopic images.

There exist methods in multicolour photography and in stereoscopic photography, in which three or two part images are projected unto each other. This method however cannot be used for television reception, because the images cannot be brought to coincidence with sufficient precision.

The last mentioned difficulties do not exist, if the part images are produced one after the other on the screen of one and the same cathode ray tube, because then the errors in deflection are the same for all pictures, so that the pictures can be brought to coincidence. It is however difficult to construct a screen for a cathode ray tube radiating in succession in three different basic colours. There remains therefore only the possibility to use three colour filters moving synchronously to the vertical deflection in front of a white luminescent screen, and in case light filters consisting for instance of gelatine attached to a motor driven disk are used, this method can be realised. It has however the drawback, that a pronounced flicker appears in the image, because the time between the changes of colour is too large. Even if the image periods per second would be increased it would be difficult to eliminate flicker.

The same applies to the stereoscopic image reception, in which instead of the coloured filters a polarisation filter is used. The image must then be viewed through a polarising eye-glass.

All the drawbacks of these different methods are avoided according to the invention.

Further features of my invention will be apparent as will be specifically pointed out in the following description forming a part of the specification, but I do not limit myself to the embodiments of the invention herein described, as various forms may be adopted within the scope of the claims.

Referring to the drawing:

Fig. 1 shows the situation of the lines on the screen of a cathode ray tube.

Fig. 1A shows a side view of the three line elements disposed close to the bottom of the cathode ray tube 2.

Fig. 2 shows a section through an arrangement including a cathode ray tube, a mirror wheel, and a viewing screen and

Fig. 3 shows a similar arrangement for producing stereoscopic images.

Fig. 1 shows the screen 10 of a cathode ray tube 2. The left hand side of the figure shows a front view of the screen and the right hand side a side view. The screen consists of three lines of luminescent material A, B, C, each line luminating upon impingement of the cathode ray in a different colour, for instance blue, yellow and red. The screen may for instance consist of zinc cadmium sulfide, the spectral wave length of the different lines of the screen is obtained by using a different content of cadmium sulfide, so that each line luminesces in one of the basic colours.

Fig. 2 shows the complete arrangement. The cathode ray tube 2 contains a line deflecting system 11 and an auxiliary deflecting system 3 moving the ray vertically to the direction of the lines. A lens 5 is situated in front of the cathode ray tube, and an image of the screen is projected over a polygonal mirror or mirror wheel 4 onto the viewing screen 6. The mirror wheel is driven by a suitable motor not shown in the drawing.

The operation of the device is as follows:

The cathode ray 1 of the tube 2 scans line A under the influence of deflecting system 11. It is then moved by the deflecting device 3 to line B, scans line B and is moved to line C. After line C has been scanned the deflecting device 3 directs the ray again to line A and the cycle is repeated. The deflection field 3 is synchronised with the frequencies of the line deflecting field in such a manner, that its frequency is exactly one third of the line frequency. According to the invention the deflection of field 3 and the distance between the three lines is so arranged, that the lines are brought to coincide by the compensating device. In the present case the mirror wheel 4 is used for building up the image in the direction vertical to the lines and at the same time as compensating device. The speed of rotation of the mirror wheel is so chosen with respect to the image frequency, that the mirror wheel rotates once for a whole number of images. The mirror wheel rotates very slowly and does neither produce vibrations nor acoustical disturbances.

During the line period the image of line A

is moved by a mirror of wheel 4 for a small distance on the viewing screen. The deflecting field 3 moves the cathode ray in the same interval of time, so that line B is scanned and the image of line B is produced on exactly the same place of the viewing screen 6 as line A, because the mirror has moved in the same time for a distance, which compensates the movement of the cathode ray under the influence of the deflecting field 3. The same applies for the scanning of line C. When the three lines are scanned, the scanning of line A is repeated and a picture of line A is produced on the viewing screen 6 adjacent to the picture of the three foregoing lines.

Instead of the mirror wheel a suitable device for producing the compensating movement of the light ray can be used. If a stereoscopic image shall be produced only two lines are arranged on the luminescent screen. Fig. 3 shows such a device. The cathode ray tube 2 contains a screen with two lines A and B. In front of the screen two strips 8 and 9 of polarising material are arranged, which produce a polarisation in two directions perpendicular to each other. For separating and viewing the two components a polarising filter glass 7 is used. This glass is arranged in front of the eye of the observer and the polarising directions must correspond to the directions of filters 8 and 9 in front of the lines. The screen must be made of such a material, that no depolarisation of the light is effected.

What I claim is:

1. A television receiving system adapted to reproduce images of light including a group of different characteristic light components, comprising a plurality of spatially displaced light-producing elements each individually corresponding to one of said characteristic components, means, including an electron discharge device for successively scanning said elements, for successively reproducing said characteristic components, a viewing screen, and means for superimposing the successively reproduced characteristic light components from said elements into a single line of light on said screen including said group of characteristic components and for successively spatially displacing subsequent groups of characteristic light components to produce scansion of said screen and reproduction of the transmitted image.

2. A television receiving system adapted to reproduce images of light including a group of different characteristic light components, comprising a plurality of spatially displaced light-producing elements each individually corresponding to one of said characteristic components, means, including an electron discharge device for successively scanning said elements, for successively reproducing said light components, a viewing screen, and a rotating light deflecting member for superimposing the successively reproduced characteristic light components from said elements into a single line of light on said screen including said group of characteristic components and for successively spatially displacing subsequent groups of characteristic light components to produce scansion of said screen and reproduction of the transmitted image.

MANFRED VON ARDENNE.
